UNITED STATES PATENT OFFICE.

WILLIAM N. PILKINGTON, OF ST. HELENS, ENGLAND, ASSIGNOR TO PILKINGTON BROTHERS LIMITED, OF ST. HELENS, ENGLAND.

DESIGN FOR SHEET GLASS.

Application filed January 6, 1923. Serial No. 4,824. Term of patent 14 years.

To all whom it may concern:

Be it known that I, WILLIAM NORMAN PILKINGTON, subject of the King of Great Britain, residing at St. Helens, in the county of Lancaster, England, have invented a new, original, and ornamental Design for Sheet Glass, of which the following is a specification, reference being had to the accompanying drawing, forming a part thereof.

The design consists in the pattern formed by the repetition of fanciful semicircular

contours arranged in staggered formation on sheet glass to which the design is to be applied.

I claim:—

The ornamental design for sheet glass as shown.

W. N. PILKINGTON.
